SURFACE ORNAMENTATION OF WALLS.

No. 18,467.

Patented July 17, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,467, dated July 17, 1888.

Application filed March 17, 1888. Serial No. 267,580. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photograph is a face or plan view of my design.

My design consists in the quadrangular pyramidal elevation A. Adjacent to said elevation A appear four triangular pyramidal ele-

vations, B. The base of each of said elevations B is in the form of an isosceles triangle. The longest edge of the base of each pyramid 15 B appears to meet an edge of the pyramid A.

I claim—

The design for surface ornamentation of walls, &c., substantially as herein shown and described.

FREDERICK KOSKUL.
